CONTAINER WITH ROTATABLE SPOUT

Frank J. O'Brien and Henry A. Fink, Pelham
Manor, N. Y., assignors to Continental Can
Company, Inc., New York, N. Y., a corporation
of New York

Application November 5, 1936, Serial No. 109,377

1 Claim. (Cl. 221—11)

The present invention relates to new and useful improvements in dispensing containers, and more particularly to a metal container having a combined closure and pouring spout attached thereto.

5 An object of the invention is to provide a closure means of the bung type secured to an upstanding flange on a can top, which bung is provided with a raised portion having a scored section removable to provide a pouring opening, 10 and wherein the spout is secured to the bung and raised portion of the can top so as to rotate thereon.

15 A further object of the invention is to provide a combined closure and bung of the above type wherein the spout has an integral projecting member contacting with the upper face of the raised portion for controlling the pouring opening.

In the accompanying drawing:

Figure 1 is a top plan view of the dispensing 20 container showing the pouring spout in a closed position.

Figure 2 is a similar view showing the pouring spout in a dispensing position.

Figure 3 is an enlarged sectional view taken 25 along the line 3—3 of Fig. 1.

Figure 4 is an enlarged sectional view taken along line 4—4 of Fig. 2.

The invention relates generally to a metal container for dispensing oil or other liquid products. 30 The container ends are secured to the body portion preferably by double-seaming. The top end is provided with a mouth having an upstanding outwardly tapering flange surrounding the same. A cuplike bung fits within said mouth and contacts with the flange for closing the mouth. The bung has an overhanging skirt provided with a depending portion which is spun into contact with the outer face of said upstanding flange for effecting a tight seal between the can end and the 40 bung. The bung is provided with a central raised portion which is scored to provide a removable section for forming a pouring opening. A spout having a tapered pouring lip is attached to the bung. Said spout is provided with a depending 45 flange which surrounds the skirt of the bung and contacts with the outer face thereof for rotatably securing the spout to the bung. The spout is also provided with an integral projecting member which overlies and contacts with the raised portion of the bung and is so disposed as to cover the pouring opening when the spout is turned to a position within the limits of the can top, and to uncover said opening when the spout is turned to pouring position.

55 Referring more in detail to the drawing, the container consists of a body portion 5 having a top end 6 double-seamed thereto as indicated at 7. The top end is formed with a mouth 8 surrounded by an upstanding outwardly tapering flange 9. A 60 cup-shaped bung 10 fits within said mouth and

contacts with said flange 9. The bung has an overhanging skirt portion 11, which skirt has a depending portion 12 spun or crimped around the upstanding flange 9 for effecting a tight seal between the bung and the can end. The bung 5 also has a raised central portion 13 provided with a score line 14 which provides a removable section for forming a pouring opening.

Attached to the bung 10 is a pouring spout 15 which has a pouring lip 16 and a depending 10 flange 17. Said depending flange surrounds the skirt of the bung and contacts with the outer face thereof for rotatably securing the spout to the bung. The raised portion 13 of the bung is so dimensioned that its upper face lies slightly above 15 a plane containing the upper edge of the skirt. The spout 15 is provided with an integral horizontal projecting member 18 which overlies and contacts with the outer face of the raised portion of the bung.

When the spout is turned to a position so as to overhang the double seam, the projecting member carried by the spout is moved so as to uncover the scored section in the raised portion of the bung. The metal can be ruptured by pressure along the scored line, and this will provide a pouring opening. When the spout is moved to a position within the limits of the can top, then the integral member 18 carried by the spout will move so as to cover the pouring opening and thus 30 temporarily close the can.

It will be obvious that minor changes in the details of construction and arrangement of the parts may be made without departing from the spirit of the invention as set forth in the appended 35 claim.

We claim:

A can comprising a body portion and a can top having a mouth with an upstanding outwardly tapering flange and a cuplike bung adapted to 40 fit within said mouth and contact with said flange, said bung having an overhanging skirt provided with a depending portion snugly fitting the outer face of said upstanding flange for sealing the bung to the can, said bung having a central raised portion scored to provide a removable section for forming a pouring opening, and a spout having a pouring lip and a depending flange surrounding the skirt of the bung and contacting with the outer face thereof for rotatably securing 45 said spout to the bung, said spout having an integral projecting member overlying and contacting with said raised portion and disposed so as to cover the pouring opening when the spout is turned to a position within the limits of the can 50 top, and uncovering said opening when the spout is turned to pouring position.
